UNITED STATES PATENT OFFICE.

BERNARD BRANNER, OF NEW YORK, N. Y.

DESIGN FOR A MAT.

45,175.

Specification for Design.

Patented Feb. 3, 1914.

Application filed December 3, 1913. Serial No. 804,516. Term of patent 7 years.

To all whom it may concern:

Be it known that I, BERNARD BRANNER, a citizen of the United States, and a resident of the city of New York, county of New York, and State of New York, and whose post-office address is 868 Manida street, in said city, have invented a new, original, and ornamental Design for Mats, of which the following is a specification.

Reference is to be had to the accompanying drawing, in which the figure shown is a plan view of the mat.

I claim:

The ornamental design for a mat as shown.

Signed at the city of New York, county of New York, and State of New York, this 2nd day of December, 1913.

BERNARD BRANNER.

Witnesses:

H. RADZINSKY,
JULIUS BREGMAN.
